[57] **CLAIM**

The ornamental design for a housing for an electrical connector, as shown and described.

DESCRIPTION

FIG. 1 is a perspective view of a housing for an electrical connector showing our new design;

FIG. 2 is a top plan view thereof;

FIG. 3 is a front elevation view thereof;

FIG. 4 is a rear elevation view thereof;

FIG. 5 is a bottom plan view thereof;

FIG. 6 is a right elevation view thereof, the left side elevation view being a mirror image;

FIG. 7 is a section view taken at line 7—7 of FIG. 3;

FIG. 8 is a section view taken at line 8—8 of FIG. 3;

FIG. 9 is a perspective view of a housing for an electrical connector showing a second embodiment of our new design;

FIG. 10 is a top plan view thereof;

FIG. 11 is a front elevation view thereof;

FIG. 12 is a rear elevation view thereof;

FIG. 13 is a bottom plan view thereof;

FIG. 14 is a right elevation view thereof, the left side elevation view being a mirror image;

FIG. 15 is a section view taken at line 15—15 of FIG. 11;

FIG. 16 is a section view taken at line 16—16 of FIG. 11;

FIG. 17 is a section view taken at line 17—17 of FIG. 11.
